UNITED STATES PATENT OFFICE.

ROBERT G. DYSON, OF TROOPER, AND HARVEY S. PLUMMER, OF FAIRVIEW VILLAGE, PENNSYLVANIA, ASSIGNEES TO FRANKLIN AIR COMPRESSOR WORKS, OF NORRISTOWN, PENNSYLVANIA, A CORPORATION OF PENNSYLVANIA.

COOLING CONSTRUCTION FOR CYLINDERS.

Application filed June 8, 1923. Serial No. 644,283.

To all whom it may concern:

Be it known that we, ROBERT G. DYSON and HARVEY S. PLUMMER, citizens of the United States, residing, respectively, at 5 Trooper, in the county of Montgomery and State of Pennsylvania, and Fairview Village, in the county of Montgomery and State of Pennsylvania, have invented certain new and useful Improvements in Cooling Constructions for Cylinders, of which the following is a specification.

It is well known that the cylinders of air compressors, engines and similar devices become hot during use and that it is necessary 10 to cool such cylinders in order to prevent them from becoming overheated.

Various structures have been employed prior to our invention for the purpose of effecting said cooling, but they have not been 15 entirely satisfactory.

One object of our invention is to provide a simple, durable and inexpensive construction for such cylinders which will effect the proper cooling thereof.

20 Another object is to so form our invention that it can be readily manufactured and will be of a practical and strong formation.

These objects and other advantageous ends which will be set forth hereinafter, we attain 25 in the following manner, reference being had to the accompanying drawing in which—

Figure 1 is a fragmentary elevation of an air compressor having a cylinder constructed in accordance with our invention, and

30 Figure 2 is a section taken on the line 2—2 of Figure 1.

Referring to the drawings, 3 represents the body portion of an air compressor having an upright cylinder 4. Said cylinder 40 may have the usual bore 5 in which the piston operates for effecting the compression. The cylinder 4 may be cast integral with the body portion 3 and includes an exterior rib 6 in the form of a helix, the turns or 45 convolutions of which start adjacent the lower part of the cylinder and ascend as clearly shown in Figure 1 of the accompanying drawing. This helical rib 6 is preferably cast integral with the cylinder and thus 50 forms a helical groove 7 between the convolutions or turns of the rib 6, said groove starting with its lower end at 8 and terminating with its upper end at 9.

It will be noted by reference to the drawing that the extreme ends 8 and 9 are flush 55 with the outer surface of the cylinder and extend gradually inward until they reach the full depth of the groove. On account of this construction and especially due to such shape of the top end 9 of the groove, any 60 heated air passing upward in the helical channel provided by the groove will be deflected laterally from the cylinder when reaching the top end portion 9 of the groove and therefore the heated air will not pocket 65 in the groove. Thus the heated air quickly passes off and the cylinder is effectively kept cool.

Furthermore, we preferably taper the upper end of the groove, as shown in Figure 1, 70 so that the air, when passing through the uppermost convolution of the groove, will enter the tapered portion of the groove and here again provision is made to cause the lateral deflection of the heated air away 75 from the cylinder.

Having thus described our invention, what we claim as new and desire to secure by Letters Patent is:

1. A cylinder having in its outer surface 80 a helical cooling groove exposed to the atmosphere, the convolutions of said groove extending in the direction of the height of said cylinder, said groove at its upper end being flush with the outer surface of the cylinder and extending gradually inward until it reaches the greatest depth of said groove, said groove being so formed as to produce a helically projecting rib whose outer surface is in alignment with the outer 85 surface of the cylinder.

2. A cylinder having in its outer surface 90 a helical cooling groove exposed to the atmosphere, the convolutions of said groove extending in the direction of the height of said cylinder, said groove at its upper end being flush with the outer surface of the cylinder and extending gradually inward until it reaches its greatest depth, said groove tapering in width near each end to its point of junction with said outer surface of the cylinder, said groove being so formed 95 as to produce a helically projecting rib whose outer surface is in alignment with the outer surface of the cylinder.

3. A cylinder having in its outer surface 100

a helical cooling groove exposed to the atmosphere, the convolutions of said groove extending in the direction of the height of said cylinder and having its upper end terminating within the height of said cylinder, the intervening rib formed by said groove being flush with and blending into the sur-

face of the top portion of said cylinder, whereby there is no projecting end of the rib to form an obstruction. 10

In testimony whereof we have signed our names to this specification.

ROBERT G. DYSON.

HARVEY S. PLUMMER.
